CORRESPONDENT'S CASE

Maurice Lifton, Belle Harbor, Long Island, N. Y.,
 assignor to The Lifton Mfg. Co., a copartner-
 ship composed of Maurice Lifton, Aaron Lifton,
 and Benjamin Lifton, New York, N. Y.

Application January 23, 1936, Serial No. 60,394

5 Claims. (CL. 150—1.6)

This invention relates to correspondence cases or envelopes, especially to such a case having complementary flaps adapted to form a gusset or gussets, and my improvements are of particular utility when embodied in the construction of a correspondence case comprising side parts opening swingingly away from each other around a joining part at the base of the case, although I contemplate the use of my improvements in any similar type of case for use in which they are adapted by their nature.

An object of the invention is to provide a case of this class with an unusually strong reinforcement, taking the form of a U-shaped wire frame which constitutes a departure from existing reinforcements in the respect that the U is inverted, so that the side bars of the frame are connected by a cross-bar extending from edge to edge of the case at the upper margin thereof.

Another object of the invention is to provide a case of the aforesaid type with such a wire frame that each region of the case in which such an inverted U-shaped reinforcement is provided will not collapse, but will retain its shape, the frame aiding to maintain the case with uniform breadth and thickness.

A correspondence case so reinforced is much stronger than conventional cases of this general type.

A further object of the invention is to provide a case of the type in which the two sides, when swung upward into closed position, are united by a running hookless fastener, with a wire frame included within a pocket formed by a strip of leather or similarly strong, flexible material superimposed upon the conventional strip of flexible material upon the edge of which the hookless fastener elements are mounted, so that the reinforcing wire frame is held in place by the laminated or double ply wall constituted by these two superimposed strips, through which is run a double row of stitching, one row on each side of the wire.

A cognate object is to furnish an unusually strong base for such a hookless fastener strip, so that by provision of the wire frame parallel with the U-shaped run of the fastener, any tendency of the latter to tear its supporting strip away from the lip of the flap is obviated, and the smooth operation of the fastener runner is facilitated.

Other features and objects of the invention will appear as the description of the particular physical embodiment selected to illustrate the invention progresses.

In the accompanying drawing, like characters 55 of reference have been applied to corresponding

parts in the several views which make up the drawing, in which:

Fig. 1 is a view in perspective of a correspondence case or envelope, in the construction of which the present invention has been embodied; 5

Fig. 2 shows the case of Fig. 1 opened out to reveal its interior structure;

Fig. 3 is a view thereof on an enlarged scale in end elevation, partly in vertical section on the line 3—3 of Fig. 1;

Fig. 4 is a detail view in perspective of one of the U-shaped wire reinforcements, shown separately;

Fig. 5 is a greatly enlarged fragmentary detail view in vertical section on the line 5—5 of Fig. 1. 15

In the now-preferred embodiment of the invention selected for illustration and description, the reference character 1 designates generally a piece of somewhat flexible strong leather which forms the exterior walls of a correspondence case 20 or envelope, corresponding in general contour to a known type of such cases, this piece being adapted to be flexed transversely along its median region 2 so as to form integral panels 3 and 4 constituting the sides of the case when closed, as 25 in Fig. 1.

Sliding handles 5 of known form are provided, in the instance illustrated, and a lining 6 of leather, cloth or other suitable material is secured to the piece 1 by any suitable means, such 30 as the stitching 7, 8 and 9.

The first-named stitching 7, includes a U-shaped run of stitches extending from the median region 2 at each side completely around the margin of the panel 3 and not only uniting the 35 contiguous edges of that panel and the lining, but, as shown in detail in Fig. 5, also uniting thereto a strip 10 of leather or other suitable material which serves the purpose of a closure flap having the nature of a gusset element, and 40 also serves the important purpose of a base strip to which is attached, as by stitches 11, 12, a strip 13 of fabric which may desirably be of the conventional type employed as a support and attachment strip, for the elements 14 of a hookless 45 fastener means adapted to co-act with a complementary series 15 of such elements carried by a similar attachment strip 16 stitched, as at 17, 18 to a closure or gusset element 19 which is symmetrically disposed on the margin of panel 4 and 50 is united to the edge thereof by the stitching 9, with the contiguous edge 20 of the lining 6 embraced therebetween.

The conventional operator member 21 for effecting the running union of the hookless fas- 55

tender elements in known manner is adapted to occupy the position illustrated at the right-hand of Fig. 1 when the envelope is open; and to occupy the position shown at the left-hand of Fig. 1 when the envelope is closed.

In order to permit the hookless fastener run to extend well within the confines of the case sides at the regions 2 respectively, the terminal 22 of each of the flap strips 18 and 19 is bent 10 around from a position of parallelism with the lateral margin of the side to which it is attached, to a position in parallelism with the median line 2-2 at the bottom.

A bottom strip 23 of suitably heavy flexible 15 material, such as leather or fabric is secured in place by the stitching 8, which preferably runs only through the lining 6 and the bottom strip 23, the lining 6, flap strips 18 and the above described ends 22 of the runner strips 13 and 18 20 being desirably assembled before the assembly of the lining and flap strips with the piece 1, and the performance of the stitching operation which unites the lining 6 and flaps 18, 19 around their contiguous margins, as at 7, 9.

25 The ends of the strip 23 are formed with V-shaped notches, to facilitate the tucking in of the flap-strip terminals 23, and the stitching 8 follows the contour of these notched ends, as shown in Fig. 2.

30 In pursuance of the invention, the provision of frame members 24, each composed of a single piece of stiff wire, bent in the form of an inverted U, as shown in Fig. 4, is accomplished preferably at the same time that the rows of stitches 11, 12, 35 and 17, 18 are run through the plies 18, 13 and 19, 16 respectively, and as these reinforcement members are desirably identical in form, and similarly held in place, the emplacement of only one will be described.

40 Each occupies a pocket formed between the plies 18, 13 and 19, 16, as the case may be, and confined by the stitches 11 and 12 in the one instance and the stitches 17 and 18 in the other instance.

45 Preferably an added strip 25 is secured over the runner strip 13 and a similar strip 25 is secured over the runner strip 16 by the stitching, for the sake of strength and improved finish, and it will be seen from Fig. 3 that the stitching 50 and strips secured thereby runs along the complete extent of the U-shaped member, confining not only the cross-part which is designated 24 in Figs. 4 and 5, but also each of the shanks 26, which as will be readily understood are disposed 55 in parallelism with, and adjacent to, the lateral margins of the case.

From the foregoing it will be seen that each of the members 24 derives its support entirely from one of the flaps 18, 19 and in a sense is a floating member, so that while rigid enough to hold the lips of the flaps at the right position for easy operation of the runner 21, and, more important, to aid in maintaining the desired width and thickness of the case, these floating 65 members do not interfere with a desirable flexibility of the flaps 18, 19 in their capacity as supplemental parts of what is virtually a gusset extending around the top and upright sides of the case, when closed, as in Fig. 1.

70 An especially novel and useful effect is secured by the fact that the free ends 27 of the shanks 26 of the wire member permit an important yielding or flexibility at the regions 2 in the closure of the bottom, while tending to hold the joined flaps in exactly the proper position neces-

sary to impart good shape to the gusset at this critical region.

They prevent the flaps from bulging and at the same time prevent their collapse inwardly.

Ample space is afforded within the confines 5 of the case for the insertion of correspondence, and the drawing illustrates a case which is fitted with conventional sets of pockets 28 and 29, secured to the lining 6 at each side; also a blotter tablet 30.

I claim:

1. A correspondence case or envelope of the class described, comprising swinging side panels joined along one edge and each having a marginal flap of flexible material extending around 15 the other three edges, being provided with means to join the lips of said flaps, and each flap being characterized by a U-shaped reinforcement means secured around said lip, near the free margin of said lip, and adapted to float bodily 20 therewith.

2. A correspondence case or envelope of the class described, comprising swinging side panels joined along one edge and each having a marginal flap of flexible material extending around 25 the other three edges, being provided with means to join the lips of said flaps, and each flap being characterized by a U-shaped reinforcement means secured around said lip, near the free margin of said lip and adapted to float bodily 30 therewith, each of said reinforcement means including a piece of rigid wire stock having sensibly 35 resilient shank portions, each of said wire reinforcement pieces being enclosed within a pocket formed by stitching a fastener strip and an added strip to each flap.

3. A correspondence case or envelope of the class described, comprising swinging side panels joined along one edge and each having a marginal flap of flexible material extending around 40 the other three edges, being provided with means to join the lips of said flaps, and each flap being characterized by a U-shaped reinforcement means secured around said lip, each of said reinforcement means including a piece of rigid 45 wire stock having sensibly resilient shank portions, and characterized by having said wire member enclosed within a pocket formed by stitching at least one added strip to said flap, said added strips being provided along their respectively free edges with hookless fastener elements, and a runner to complete the hookless fastener joint between said flaps.

4. A correspondence case or envelope of the class described, comprising swinging side panels 55 joined along one edge and each having a marginal flap of flexible material extending around the other three edges, being provided with means to join the lips of said flaps, and each flap being characterized by a U-shaped reinforcement 60 means secured around said lip, and by having the side panels of said case formed of a single piece of sensibly stiff leather, a leather lining co-extensive with said panels, and rows of stitching extending through, and securing together, the 65 lateral margins of said panel-piece, said lining and said flap-strips around three sides of each panel, a flexible strip provided with hookless fastener elements secured to each flap by rows of stitches spaced apart to form a pocket, and further characterized by having said reinforcement formed as a wire member confined within said pocket and supported in floating disposition by its flap.

5. A correspondence case or envelope as set 75

forth in claim 1, and characterized by having the side panels of said case formed of a single piece of sensibly stiff leather, a leather lining co-extensive with said panels, and rows of stitching extending through, and securing together, the lateral margins of said panel-piece, said lining and said flap-strips around three sides of each panel, and further characterized by pockets se-

cured to said lining and constituting therewith and with said flaps an entity formed separately from said panels, said pockets being surrounded on three sides, and protected, by said U-shaped reinforcement, when embodied in the structure 5 of said correspondence case or envelope.

MAURICE LIFTON.
